United States Patent Office

Des. 228,447
Patented Sept. 25, 1973

228,447

DISPENSING CLOSURE OR SIMILAR ARTICLE

Alan Glazer, Brett Lane, R.F.D. 2, Bedford, N.Y. 10506

Filed Sept. 18, 1972, Ser. No. 289,985

Term of patent 14 years

Int. Cl. D9—07

U.S. Cl. D9—279

FIG. 1

FIG. 2

FIG. 3

FIG. 4

FIG. 5

FIG. 1 is a perspective view of a dispensing closure or similar article, showing my new design;

FIG. 2 is a top plan view;

FIG. 3 is an elevational view;

FIG. 4 is a bottom plan view; and

FIG. 5 is a vertical axial view.

I claim:

The ornamental design for a dispensing closure or similar article, substantially as shown.
